UNITED STATES PATENT OFFICE.

CLAUDE A. CLARK, OF SYRACUSE, NEW YORK, ASSIGNOR TO HUMPHREY GAS PUMP COMPANY, A CORPORATION OF NEW YORK.

INTERNAL-COMBUSTION PUMP.

1,282,757.

Specification of Letters Patent. Patented Oct. 29, 1918.

Application filed December 7, 1915. Serial No. 65,526.

To all whom it may concern:

Be it known that I, CLAUDE A. CLARK, a citizen of the United States, residing at Syracuse, in the county of Onondaga, State of New York, have invented a new and useful Improvement in Internal-Combustion Pumps, of which the following is a specification.

My invention relates to improvements in internal combustion pumps. The object is to provide improved means for introducing the charge into a two-stroke cycle pump and keeping the several ingredients, such as gas and air, forming the combustible mixture, 10 separate until the same are delivered to the underside of a movable diaphragm which is adapted to lie against the head of the expansion chamber.

Referring to the drawings, which illustrate merely by way of example, a suitable embodiment of my invention—

Figure 1 is a vertical section showing my improvements.

Fig. 2 is a top plan view.

Fig. 3 is a horizontal section on line 3—3 of Fig. 1.

Fig. 4 is a horizontal section on line 4—4 of Fig. 1.

Fig. 5 is a fragmentary vertical section, 30 on an enlarged scale, of the movable diaphragm and associated parts.

Fig. 6 is a vertical section on an enlarged scale showing the diaphragm 8 in the lower position.

35 Figs. 7 and 8 are sectional details on enlarged scale showing the valve member 32 in the closed and open positions respectively.

Similar numerals refer to similar parts throughout the several views.

40 In Fig. 1, 7 represents the expansion chamber which is adapted to connect at its lower end with a play pipe, not shown, in which a column of liquid is adapted to reciprocate. A diaphragm 8 is fitted with an easy 45 or movable fit in the expansion chamber or cylinder 7, and is adapted to have a vertical reciprocating movement therein. To this diaphragm 8 are fitted the concentric tubes 9 and 10, which are secured at their upper ends to the annular plate or cap 11, and are held in position between said diaphragm 8 and cap 11 by the tie bolts 12.

50 Fitted to the top of expansion chamber or cylinder 7 is the head 13. In this head 13 the tube 10 has a movable fit, which fit is

made substantially air-tight by means of the gasket or packing 14.

Mounted on a suitable framework 15 extending from the top of the head 13, is the cap 16 bolted to said framework. This cap 16 is provided with a downwardly extending nozzle 17 into which is threaded the upper end of pipe 18. This nozzle 17 is in communication with a source of gas supply, by means of a suitable conductor not shown. 60 The pipe 18 extends downwardly and supports at its lower end the annular body 19 into which it is threaded, which annular body 19 forms a part of, or co-operates with the head 13 of said cylinder 7. Body 19 is 65 provided with the annular packing or gasket 20 which forms a movable gas-tight fit with the inner surface of the inner tube 9.

The annular body 19 is provided with the port 21 between the bore of the pipe 18 and the chamber 22. In chamber 22 is provided the valve 23 delivering to the space above the diaphragm 8, and within the tube 9, when the diaphragm descends in chamber 7.

Arranged around the head 13 near its periphery are three valves 24 adapted to deliver into the air space surrounding tube 10 above the diaphragm, in the expansion chamber 7, when the diaphragm 8 descends. Valve 23 and valve 24 are substantially similar in construction. Air gates 25 are also provided in the peripheral walls of the head 13 for admitting air into the annular space 26 above the valves 24.

Gas is conducted through pipe 18 and port 21 to chamber 22 above valve 23. It will be understood that pipe 18 is to be connected with a suitable gas supply, not shown.

A supplemental gas intake pipe 27 is also provided for introducing gas, when required, past valve 29, into the air space surrounding tube 10, in chamber 7 above diaphragm 8, when said diaphragm descends. This supplemental gas pipe is controlled by the cock 28. A supplemental air intake 100 valve controlled pipe 30 is connected with the gas pipe 18 for introducing air with said gas, when required.

The diaphragm 8 is provided with channels 31, leading from the gas space within 105 tube 9. These channels are controlled by a valve member 32 normally held closed by springs 33. The diaphragm 8 is also provided with the channels 34 leading from the air space surrounding tube 10 above the dia- 110

phragm 8. These channels are similarly controlled by a spring valve 35.

A buffer 36 is provided for engaging the cap 11 for cushioning the downward movement of the plunger tubes 9 and 10.

A spark plug 37 is provided in the wall of chamber 7 for igniting the charge. The current to this plug is controlled by the mechanism indicated at 38 which is actuated by the cap 11, at about the end of its upward stroke.

The operation is as follows:—Assuming, at the beginning of the cycle, that the diaphragm 8 is up against the head 13 as shown in Fig. 1, and a combustible mixture is below the diaphragm and under compression; the explosive mixture is ignited by means of the spark plug 37, or other suitable device, and the expanding gas forces the water down in the play pipe until the expanded gas has reached approximately atmospheric pressure. At this point the exhaust valves 39 are forced open by their springs 40, and the diaphragm 8 drops to approximately the position shown in Fig. 6, due to its weight, and if the pressure falls a little below atmospheric, the diaphragm will be further accelerated, due to the vacuum on the underside thereof caused by the momentum of the outwardly moving water column, and to the differential area of the plunger.

The dropping of the diaphragm 8, pushes the burnt gases down through the exhaust valves 39, at the same time drawing in gas through valve 23, and air through valves 24. When the diaphragm falls to a point just above the exhaust valves 39, it will be brought to rest by the cap 11 dropping onto the buffer 36, and will remain there with the gas and air above it, kept separate from each other and from the exhaust gases below it, until the return stroke of the water column in the play pipe.

The water rising in the play pipe, forces the remaining exhaust gases out through the exhaust valves 39, until the water reaches said exhaust valve and thereby forcing them shut. The water reaches the diaphragm 8 practically at the same time it reaches the exhaust valves and starts the diaphragm upward, compressing the gas and air above it. As the pressure per square inch below the diaphragm must be equal to that above the diaphragm, on account of the openings through the diaphragm which are closed merely by the check valves 32 and 35 opening downward, there will be a tendency for the diaphragm to travel faster than the water, owing to the difference of area caused by the thickness of walls of the plunger, or in the present case, the difference between the outside circumference of tube 10 and the inner circumference of tube 9, so that the air and gas will pass through channels 31 and 34, past the valves 32 and 35 from above the diaphragm to beneath the

diaphragm. The diaphragm will finally come to rest, against the head 13, as in Fig. 1, with the air and gas all below it, which air and gas will have become mixed, as the valve guards 41 and 42 direct the streams of air and gas together, when coming through the diaphragm, so that we will be back to the original point, the diaphragm against the cylinder head and a combustible mixture compressed below it, when the cycle continues.

It will thus be seen that with the diaphragm 8 in the lower position as shown in Fig. 6, the gas contained within the tube 9 is separated from the air surrounding tube 10, within the combustion chamber 7, until the burnt products have been expelled from below the diaphragm 8; that as the diaphragm moves upwardly toward the position shown in Fig. 1, the air and gas are transferred to beneath the diaphragm thereby forming together an explosive or combustible mixture for the beginning of the next cycle as explained.

It is desirable to design the pump so that the ratio of gas space to air space above the diaphragm, shall be approximately the ratio of gas to air which provides an explosive mixture. If the gas space is slightly less than this proportion, the mixture can be enriched by opening the cock 28, and letting a small amount of gas into the air space, surrounding tube 10, which will mix with air before the air is transferred through the diaphragm 8. So long as this gas is not sufficient to produce an explosive mixture, there is no objection to this method of regulation. On the other hand if the mixture is inclined to be too rich, a little air may be introduced through valve-controlled pipe 30, with the gas entering the gas space through pipe 18. These two valves regulate the mixture.

What I claim is:—

1. In the method of reciprocating a liquid column by the expansion of a combustible charge against said column the following steps introducing into the expansion space the components of said combustible charge and maintaining the said components separated from each other while in said expansion space and also from the burnt products of a previous charge, until the expulsion from said expansion space of said burnt products and then mixing said components together under pressure and igniting the same.

2. In the method of reciprocating a liquid column by the expansion of a combustible charge against said column to cause the out-stroke, the following steps introducing into the expansion space the components of said combustible charge upon the outstroke of the liquid column, and maintaining the said components separated from each other while

in said expansion space and also from the burnt products of a previous charge, until the expulsion from said expansion space of said burnt products and then mixing said 5 components together and igniting same.

3. In the method of reciprocating a liquid column by the expansion of a combustible charge against said column to cause the out-stroke, the following steps introducing into 10 the expansion space the components of said combustible charge and maintaining the said components separated from each other while in said expansion space and also from the burnt products of a previous charge.

15 until the expulsion from said expansion space of said burnt products by the return stroke of the liquid column and then mixing said components together and igniting same.

4. In the method of reciprocating a liquid 20 column by the expansion of a combustible charge against said column the following steps introducing into the expansion space the components of said combustible charge and maintaining the said components separated from each other while in said expansion space and also from the burnt products of a previous charge, until the expulsion from said expansion space of said burnt products and then mixing said components 25

30 together under pressure of the return stroke of the liquid column and igniting the same.

5. In combination with means, including an expansion chamber and play pipe, for reciprocating a liquid column by the expansion 35 of a combustible charge, a tube, a diaphragm connected therewith having different pressure areas on its opposite sides, said tube and diaphragm adapted to reciprocate in the expansion chamber, as means for introducing gas and air into the expansion 40 chamber separated one from the other by the tube and diaphragm and from the products of combustion by said diaphragm and valved passages in said diaphragm for the 45 transfer of said gas and air from above to beneath the diaphragm.

6. In combination with means, including an expansion chamber and play pipe for reciprocating a liquid column by the expansion 50 of a combustible charge, a tube having its inner wall spaced from its outer wall, a diaphragm connected therewith having different pressure areas on its opposite sides, said tube and diaphragm adapted to reciprocate in the expansion chamber, as means for introducing gas and air into the expansion 55 chamber separated one from the other by the tube and diaphragm and from the products of combustion by said diaphragm and valved passages in said diaphragm for the 60 transfer of said gas and air from above to beneath the diaphragm.

7. In combination with means, including an expansion chamber and play pipe for reciprocating a liquid column by the expansion 65

70 sion of a combustible charge, a tube, a diaphragm connected therewith, the effective pressure area of its underside being greater than the effective area of its upperside, said tube and diaphragm adapted to reciprocate in the expansion chamber, as means for introducing gas and air into the expansion chamber separated one from the other by the tube and diaphragm and from the products of combustion by said diaphragm and valved passages in said diaphragm for the 75 transfer of said gas and air from above to beneath the diaphragm.

8. In combination with means, including an expansion chamber and play pipe for reciprocating a liquid column by the expansion 80 of a combustible charge, a tube, a diaphragm connected therewith having different pressure areas on its opposite sides, said tube and diaphragm adapted to reciprocate in the expansion chamber, as means for introducing gas and air into the expansion chamber separated one from the other by the tube and diaphragm and from the products of combustion by said diaphragm and valved passages in said diaphragm for the 85 transfer of said gas and air from above to beneath the diaphragm, and means for facilitating the mixture thereof.

9. In combination with means, including an expansion chamber and play pipe for reciprocating a liquid column by the expansion 90 of a combustible charge, a tube, a diaphragm connected therewith, said plunger and diaphragm adapted to reciprocate in the expansion chamber, as means for introducing gas and air into the expansion chamber separated one from the other by the tube and diaphragm and from the products of combustion by said diaphragm and valved 95 passages in said diaphragm for the transfer of said gas and air, the diaphragm having a less effective area above than beneath so that upon the return stroke of the liquid column the air and gas are transferred from above to beneath the diaphragm under pressure.

10. In combination with means, including an expansion chamber and play pipe for reciprocating a liquid column by the expansion 100 of a combustible charge, a tube, a diaphragm connected therewith having different pressure areas on its opposite sides, said tube and diaphragm adapted to reciprocate in the expansion chamber, as means for introducing gas and air into the expansion chamber separated one from the other by the tube and diaphragm and from the products of combustion by said diaphragm and valved 105 passages in said diaphragm for the transfer of said gas and air from above to beneath the diaphragm, and an ignition device and a control therefor operated by the plunger.

11. In an internal combustion pump, the 110

combination of an expansion chamber or cylinder, a valve controlled exhaust port in the lower part thereof, a diaphragm movable in said cylinder, a hollow plunger element connected therewith, a valve controlled gas supply delivering into the cylinder within the hollow plunger element and above the diaphragm, a valve controlled air intake delivering into cylinder outside the hollow plunger element above the diaphragm when the diaphragm descends and valve controlled passages leading from the gas space and air space above the diaphragm for transferring the gas and air to the space beneath the diaphragm upon its ascent.

12. In an internal combustion pump, the combination of an expansion chamber or cylinder, a valve controlled exhaust port in the lower part thereof, a diaphragm movable in said cylinder, a hollow plunger element connected therewith, having substantial gas tight movable fit in head of cylinder, a valve controlled gas supply delivering into the cylinder within the hollow plunger element and above the diaphragm, a valve controlled air intake delivering into cylinder outside the hollow plunger element above the diaphragm when the diaphragm descends and valve controlled passages leading from the gas space and air space above the diaphragm for transferring the gas and air to the space beneath the diaphragm upon its ascent.

13. In an internal combustion pump, the combination of an expansion chamber or cylinder, a valve controlled exhaust port in the lower part thereof, a diaphragm movable in said cylinder, a hollow plunger element connected therewith, said hollow plunger element having a substantially greater outer periphery than its inner periphery whereby the diaphragm has a lesser effective area above than beneath it, a valve controlled gas supply delivering into the cylinder within the hollow plunger element and above the diaphragm, a valve controlled air intake delivering into cylinder outside the hollow plunger element above the diaphragm when the diaphragm descends and valve controlled passages leading from the gas space and air space above the diaphragm for transferring the gas and air to the space beneath the diaphragm upon its ascent.

14. In an internal combustion pump, the combination of an expansion chamber or cylinder, a valve controlled exhaust port in

the lower part thereof, a diaphragm movable in said cylinder, a hollow plunger element connected therewith, a valve controlled gas supply delivering into the cylinder within the hollow plunger element and above the diaphragm, a valve controlled air intake delivering into cylinder outside the hollow plunger element above the diaphragm when the diaphragm descends and valve controlled passages leading from the gas space and air space above the diaphragm for transferring the gas and air to the space beneath the diaphragm upon its ascent, a 70
